UNITED STATES PATENT OFFICE.

FRED A. STILLE, OF RICHMOND, VIRGINIA.

DESIGN FOR A SIGNAL-LIGHT CASING.

Application filed March 16, 1926. Serial No. 16,934. Term of patent 14 years.

To all whom it may concern:

Be it known that I, FRED A. STILLE, residing at Richmond, in the county of Henrico and State of Virginia, have invented a new, original, and ornamental Design for a Signal-Light Casing, of which the following is a specification, reference being had to the accompanying drawing, forming part thereof.

Figure 1 is an elevation of the signal light casing, showing my new design.

Figure 2 is a top plan view thereof, showing my new design.

I claim:—

The ornamental design for a signal light casing, as shown.

FRED A. STILLE.
